DISPENSER

Albert Whitfield, Dearborn, Mich.

Application December 6, 1939, Serial No. 307,881

3 Claims. (Cl. 221—102)

This invention relates generally to dispensing devices, and more particularly to devices for dispensing tobacco and filling a tobacco pipe.

It is an object of the present invention to provide a new and improved dispensing device for dispensing fine cut granular or powdered material, and one in which caking of the material is prevented.

Another object of the invention is to provide a new and improved tobacco dispensing device by means of which a tobacco smoking pipe may be conveniently and quickly filled without waste of tobacco.

Another object of the invention is to provide a device of the above mentioned character which is efficient in operation and inexpensive to manufacture.

Other objects of the invention will become apparent from the following detail description taken in connection with the accompanying drawing which forms a part of this specification, and in which:

Figure 1 is a vertical, central sectional view of the improved dispensing device.

Fig. 2 is a top plan view of the device shown partly broken away and in section and also showing a smoking pipe in position to receive tobacco from the device.

Fig. 3 is a view of the device shown partly in cross section and partly in elevation, taken along the line 3—3 of Fig. 1.

Fig. 4 is a view of the device shown in cross section, taken along the line and in the direction of the arrows 4—4 of Fig. 1.

Fig. 5 is a detailed sectional view of the device, taken along the line 5—5 of Fig. 1.

Referring to the drawing by characters of reference, the device shown includes a container 10 which is preferably cylindrical in shape having a bottom wall 11 and a removable top wall or cover 12. Within the container 10, adjacent the bottom wall 11 thereof, is a substantially horizontal, removable wall or partition 13 which divides the interior of the casing 10 into an upper storage chamber 14 and a lower chamber 15, the removable partition 13 being provided adjacent the side wall of the container 10 with an opening or passage 16 for the passage or descent of tobacco or other material by gravity from the upper chamber 14 into the lower chamber 15. Positioned within the lower chamber 15, a cylinder 17 is formed integral with a plate 18 which extends across and seats on the bottom wall of the container and the plate 18 may be secured to the container bottom wall by screws

19 or by other suitable means. The longitudinal axis of the cylinder 17 extends transversely of the container 10 and the cylinder is provided with an upper opening or inlet 20 through the side wall thereof, which opening 20 registers with the opening 16 in the partition 13. The cylinder 17 is further provided with an outer reduced end portion 21 which projects externally of the casing 10 through an aperture in the container side wall adjacent the bottom thereof, the reduced portion 21 having a discharge opening in its outer end. Within the cylinder 17 there is a plunger or piston 22 adapted to discharge material, such as tobacco, from the outlet 21, the tobacco entering the cylinder through the aligned openings 16 and 20 under control of the plunger 22.

Extending vertically within the container 10 there is a manually rotatable shaft or rod 23 for actuating the piston 22, the upper end of the rod 23 projecting externally of the container and being provided with a manually operable knob 24 for conveniently rotating the rod. At its lower end, the rod 23 extends through an aperture in the removable partition 13 beneath which the rod 23 is provided with a collar 25 for seating on an upper horizontal extension arm 26 of the plate 18. The removable partition 13 unattachedly seats on the rod collar 25, cylinder 17, and on a pair of legs or pins 26a which are secured to the partition and seat on the container bottom wall 11. A crank arm 27 is secured to the lower end of the rod 23 within the lower compartment 15 and a connecting link 28 is provided having one end thereof pivotally connected to the crank arm and having the other end thereof pivotally connected to the piston 22. It will be seen that by means of the knob 24, the shaft 23 may be rotated and through the crank arm 27 and the link 28, the piston or plunger 22 may be reciprocated, the piston being moved outwardly and retracted each revolution of the knob. Preferably, a pointer 29 is provided on the knob 24 for cooperation with indicia, such as a marker 29a, for indicating the operation of the plunger 22.

In Figs. 1 and 2 of the drawing, the piston or plunger 22 is shown in its extreme outward position in which position the outer end of the piston projects slightly beyond or past the outer discharge end of its cylinder 17. When the crank 27 is rotated through 180 degrees from the position shown in Figs. 1 and 2, the piston 22 is retracted and the outer end thereof positions within the cylinder such that passage 20 is completely

or fully open to permit tobacco or other material in the upper chamber 14 to pass or fall downwardly through the opening 20 into the cylinder 17.

The removable partition 13 is provided with an upwardly extending boss 30 which is spaced from the operating rod 23 and on the upper end of the boss is mounted a rotatable, substantially horizontal plate member 31 which overlies the openings or passages 16 and 20. The plate member 31 may be rotatably mounted on the upper end of the boss 30 by a screw or by other suitable means. Carried by the plate 31 is a plurality of equally and radially spaced conveyor members 33 for conveying or pushing material or tobacco into the discharge opening 16. These conveyor members 33 may be in the form of L-shaped plate members and are secured to and depend from the under side of the rotatable plate 31 to within close proximity of the upper surface of the partition 13. Also carried by the rotatable plate member 31 is a plurality of upwardly directed agitator members in the form of pins 34 and these pins 34 and the conveyor members 33 may be rigidly secured together and to the plate member 31 by screws 35 or by other means. In addition to serving as agitators for the tobacco or other material to break up lumps or cakes thereof that might form in the storage chamber 14, the pins 34 cooperate with a drive member 36 on the shaft 23 for rotating the plate member 31. The drive member 36 includes a tubular portion 37 from which extends oppositely directed arms 38 adapted to engage the pins 34 of the plate member 31 to rotate the latter, and the drive member 36 may be secured to the rod 23 by a pin 39 provided in the tubular portion 37.

In operation, assuming that the present device is used as a dispenser of fine cut smoking tobacco, the pipe as illustrated in Fig. 1 is arranged with the bowl over the discharge end 21 of the cylinder 17 and then by means of the knob 24 the piston 22 is moved outwardly, thereby forcing a quantity of tobacco into the bowl of the pipe and at the same time closing passage 20. Upon further rotation of the knob 24, the plunger 22 is retracted and opens passage 20 permitting tobacco to fall down into the cylinder in advance of the plunger for discharge the next time the plunger moves outwardly. This operation may have to be made two or three times depending on the size of the pipe and how full it is desired to fill the bowl of the pipe with tobacco. The plunger 22 not only dispenses the tobacco in certain quantities but also is adapted to dispense the tobacco directly into the bowl of the pipe and further aids in properly packing the tobacco in the pipe bowl. When the device is operated to dispense tobacco, the plate member 31 is also rotated by rotation of rod 23 and the conveyor members 33 push or feed tobacco into the opening 16, thereby assuring that the cylinder 17 will always receive a quantity of tobacco upon return of the plunger 22 to its retracted position. In addition, when the tobacco is dispensed, the agitator members 34 operate to agitate the tobacco to prevent caking of the same thus assuring there will always be loose tobacco in position for

movement by the conveyor members 33 into the discharge opening 16.

While I have shown and described my dispenser with respect to the dispensing of pipe tobacco and the filling of a tobacco pipe, it will be understood that the device can be used for dispensing such other material as, for example, coffee, tea, sugar, etc.

What I claim is:

1. In a dispenser of the character described, a container having a lower wall provided with an opening therethrough for passage of material in said container, a cylinder within said container beneath said lower wall, said cylinder in the side wall thereof having an opening communicating with the opening in said lower wall for passage of the material into said cylinder, said cylinder having an outlet for passage of material externally of said container, a plunger in said cylinder operable to discharge material from said outlet, manually operable means externally of said container for operating said plunger, means operatively connecting said manually operable means and said plunger, means for moving material into said opening, and means operatively connecting said last-named means and said manually operable means and operable to agitate the material in said container.

2. In a dispenser of the character described, a container having an internal removable wall dividing the interior thereof into an upper storage chamber and a lower discharge chamber, said wall having an opening therethrough for passage of material from said upper chamber into said lower chamber, said container having a bottom wall having a cylinder in said discharge chamber extending transversely of said container, said cylinder having an inlet opening in the side wall thereof in communication with the opening in said removable wall and having a discharge outlet for discharge of material externally of said container, a plunger in said cylinder for discharging material from said outlet, a vertically extending manually operable shaft extending externally of said casing crank means operatively connecting said shaft and said plunger, a plate member rotatably mounted on said partition in said storage chamber, a plurality of plate members carried by and depending from said plate member for feeding the material into said opening, a plurality of spaced upwardly directed extended members carried by said plate member for agitating the material, and means carried by said shaft and cooperable with said extended members for rotating said plate member.

3. In a dispenser having a storage chamber provided with an outlet for material, a rotatable plate member overlying said outlet, a plurality of spaced depending members carried by and on the underside of said rotatable plate member for pushing material to said outlet, a plurality of spaced agitator members carried by said plate member and extending upwardly therefrom respectively from said first members, and means connecting said first-named members and said agitator members together and to said plate member.

ALBERT WHITFIELD.
